UNITED STATES PATENT OFFICE.

EVAN B. HILLMAN, HENRY KIMBER, AND HARRY DADISMAN, OF LOS ANGELES, CALIFORNIA, ASSIGNEES TO MONOLITHIC HOLLOW CONCRETE FORM COMPANY, OF LOS ANGELES, CALIFORNIA, A CORPORATION OF CALIFORNIA.

CONCRETE FORM FOR REINFORCED HOLLOW WALLS.

Application filed November 27, 1920. Serial No. 426,831.

To all whom it may concern:

Be it known that we, EVAN B. HILLMAN, a citizen of the United States, HENRY KIMBER, a subject of the King of Great Britain, and HARRY DADISMAN, a citizen of the United States, residing at Los Angeles, in the county of Los Angeles and State of California, have invented new and useful Improvements in Concrete Forms for Reinforced Hollow Walls, of which the following is a specification.

It is the object of this invention to provide a form for making concrete walls either as solid walls or hollow walls, the form also permitting of the placing of usual or any desired tie rods and reinforcing members in the wall construction.

The improved form permits of the continuous pouring of a concrete wall, the construction being so arranged that after one level of the wall has been poured and has set, that the form may be moved upwardly upon this level of the wall so as to permit pouring of the next upper level.

The invention will be readily understood from the following description of the accompanying drawings, in which:

Fig. 1 is a side elevation of a wall being constructed by means of the improved form.

Fig. 2 is a transverse section on the line 2—2 of Fig. 1.

Fig. 3 is a detail section on the line 3—3 of Fig. 2.

Fig. 4 is a detail section on the line 4—4 of Fig. 1.

In the present embodiment of the invention we have shown the improved form as employed in the construction of parallel transversely spaced walls forming a hollow wall construction. It will be apparent however, that the form is readily applicable for constructing a single wall structure, in this latter case but one of the wall forming molds of the apparatus being employed.

The two walls being constructed by means of the improved form are shown at A and B, the molds being adapted to be elevated upon the walls as soon as one level thereof has set in order that the next upper level may be poured.

Spaced standards 1 are erected between walls A and B, and are provided with sleeves 2 slidable thereon. Arms 3 project

from opposite sides of these sleeves so as 55 to overlie the walls A and B in course of construction, and side plates 4 and 5 are suspended from each of the arms 3 in transversely spaced relation so as to provide a form in which the concrete is poured in order to form the walls. 60

The side plates are made in suitable lengths, and at the meeting ends of the sections forming a side wall, lap joints are provided by means of plates 6. Suitable retaining means including hook members 7 are provided for connecting adjacent sections of a side wall. The side walls are suspended from arms 8 extending upwardly beyond the upper edges of the walls, and these arms are spaced along the side walls opposite the respective standards 1. The arms are mounted upon the laterally projecting arms 3 and may be adjustably transversely spaced in order to provide forms of varying thickness, so that walls of different thickness may be poured between the side walls comprising a form. As an instance of this arrangement a series of apertures 9 are provided along arms 3, and arms 8 may be 70 suspended from arms 3 at desired ones of these apertures as by receiving suitable fastening bolts 10 through arms 8 and said apertures. 75

The side walls depending from arms 8 85 are received against opposite sides of a wall in course of construction, and may be held against the same by means of a set screw 11 threaded through the end 12 of one of the arms 8 beyond its pivot bolt 10, and arranged to impinge against the end 12 of the other arm 8, so that the arms may be swung upon the pivots provided by bolts 10 through adjustment of the set screw. 90

By this arrangement when sleeve 2 and the side walls of the form carried thereby have been elevated so that the lower ends of the side walls are received against opposite surfaces of the upper portion of a level of the wall being constructed, the side walls may be clamped to the wall in process of construction by tightening set screw 11, and the side walls will then provide a form for the next upper level of the wall. When this level has been poured and has 105 set, the clamping engagement of the side walls may be released by reversely turning set screw 11, so that sleeve 2 and the side

walls carried thereby may be again elevated upon standard 1 and thus provide for a continuous wall construction.

The means employed for thus elevating sleeve 2, and subsequently holding the same with relation to standard 1, includes a clamping bearing 14 received upon standard 1 above sleeve 2, and having a laterally projecting arm 15. A flexible connection 16 is secured to the lower end of sleeve 2 which for this purpose is provided with lugs 17, and at its upper end this flexible connection is secured to the end of arm 15. By this arrangement when the weight of the form is upon sleeve 2, arm 15 is swung downwardly through flexible connection 16, and as a result the bearing 14 binds upon standard 1 so as to prevent said bearing sliding downwardly upon the standard, and as a consequence sleeve 2 and the form carried thereby is held in position upon standard 1 by connection 16 and the arm 15.

The means employed for subsequently elevating sleeve 2 upon the standards includes clamping bearing 17 arranged upon standard 1 above bearing 14, and having a laterally projecting arm 18 provided with a weight 19 so as to normally move the clamping bearing into binding engagement upon standard 1. A lever 20 is pivoted to arm 18, and a link connection 21 is provided between this lever and a lug 22 projecting from the lower end of sleeve 2. The lever 20 is so arranged that downward movement of the operating handle thereof will swing clamping bearing 17 against the action of weight 19 so as to destroy the binding engagement of the bearing upon standard 1, and continued downward movement of the handle of the lever will slide the bearing upwardly upon the standard. As soon as the lever handle is released the weight 19 will again cause the bearing to bind upon the standard, and lifting of the lever handle will then elevate sleeve 2 through the link connection 21. This operation is repeated until the form has been raised a sufficient distance to permit of pouring of the next upper level of the wall under construction.

It will thus be seen that I have provided a form for concrete walls by the use of which walls may be continuously poured. It will be understood that the form may be so arranged as to construct either straight, curved, or angle walls, and may be employed in the construction of partitions and the like as well as outer walls. It will also be apparent that any suitable tying or reinforcing means may be employed in connection with the walls during construction of the same.

Various changes may be made without departing from the spirit of the invention as claimed.

What is claimed is:

1. In a concrete form, a standard, a member slidable thereupon, a cross arm carried by said member, a pair of form sections pivotally connected to and suspended from said cross arm, means associated with the upper ends of said form sections for clamping their lower portions against an interposed wall, and means actuated by the weight of the slidable member and the parts carried thereby for clamping the standard to retain the supported parts at the desired elevation which means includes a clamping member that engages the standard above the slid- 70 able member, an arm projecting outwardly from said clamping member, and a chain extending from the outer end of said arm downwardly to the lower end of said slid- 75 able member.

2. In a concrete form, a standard, a mem- 80 ber slidable thereupon, a cross arm carried by said member, a pair of form sections pivotally connected to and suspended from said cross arm, means associated with the upper ends of said form sections for clamp- 85 ing their lower portions against an interposed wall, means actuated by the weight of the slidable member and the parts carried thereby for clamping the standard to retain the supported parts at the desired eleva- 90 tion, which means includes a clamping mem- 95 ber that engages the standard above the slidable member, an arm projecting outwardly from said clamping member, and a chain extending from the outer end of said arm downwardly to the lower end of said slid- 100 able member, and means connected to the slid- 105 able member and to the standard whereby said slidable member and the parts carried thereby may be moved upwardly upon said standard.

3. In a concrete form, a standard, a mem- 110 ber slidable thereon, means for moving said slidable member upwardly upon said stand- 115 ard, a clamping member positioned on the standard above the slidable member, an arm projecting outwardly from said clamping member, a chain secured to the outer end of said arm and to the lower end of said slid- 120 able member, a cross arm carried by said slidable member, a pair of vertically dis- 125 posed bars pivotally and adjustably connected to said cross arm, form sections carried by the lower ends of said arms, and a screw rod passing through the upper por- 130 tion of one of said bars and engaging the upper portion of the other, whereby the lower portions of the form sections may be moved toward each other to clamp an inter- 135 posed wall.

In testimony whereof we have signed our names to this specification.

EVAN B. HILLMAN.
HENRY KIMBER.
HARRY DADISMAN.
